UNITED STATES PATENT OFFICE.

FREDERIC SCHREIBMAN, OF TORONTO, ONTARIO, CANADA.

WOOD-BENDING APPARATUS.

1,274,459.

Specification of Letters Patent.

Patented Aug. 6, 1918.

Application filed January 5, 1917. Serial No. 140,664.

To all whom it may concern:

Be it known that I, FREDERIC SCHREIBMAN, a subject of the Czar of Russia, and a resident of the City of Toronto, Province 5 of Ontario, Dominion of Canada, have invented certain new and useful Improvements in Wood-Bending Apparatus, of which the following is a specification.

My improvements relate to the shaping of 10 moist wood for various purposes in the arts, and are designed to afford simple, inexpensive, yet effective apparatus by means of which the desired results may be expeditiously attained and rendered permanent. 15 The invention consists in the specific arrangement and construction of parts described and claimed, a distinctive feature being the method of reinforcing, sustaining and securing the bent wood until permanently set in shape, all as hereinafter fully 20 set forth.

In the accompanying drawings,

Figure 1 is a side elevation of apparatus embodying the essential features of my invention, showing the completion of the 25 operation of bending and securing a wooden blank, parts being broken away to show minor details of construction;

Fig. 2, is an end view of the parts shown 30 in Fig. 1, also partly broken away to show details;

Fig. 3, is a central vertical sectional elevation taken substantially upon plane of line 3—3, Fig. 2;

Fig. 4, is a transverse sectional elevation 35 taken upon plane of line 4—4, Fig. 3;

Fig. 5, a side or edge view of the wooden blank and its retainer before insertion in the press;

Fig. 6, is a side elevation of the bent 40 wooden blank and its retainer removed from the press.

In the arrangement illustrated in the accompanying drawings F, represents the stationary frame work of the structure generally, although I do not limit myself to the identical form of parts shown, since the same may be modified without departing from the spirit and intent of my invention

in this respect,—the essential feature being 50 the provision of suitable support for the hoist-mechanism H, and the movable die M, in proper relation and alinement with the stationary die N. I have also shown herein the apparatus as adapted to the bending 55 of a straight length of wood plank into the arc of a circle, although the essential features of my invention are applicable to the production of various other configurations of wood as a product. 60

The female or concave die N, is positioned on a suitable bed F', to which the uprights F², are attached, the superstructure being built up with cross beams, trusses etc., in any suitable manner, and the hoist mechanism being suspended on the top beams of the frame. The hoist mechanism is preferably of the type actuated by electricity although this is not a material point, since other forms of hoist mechanism may be used 70 to raise and lower the weighted male or convex die M, which is the only function performed by the hoist H, indicated symbolically in the drawings, in which h, represents the usual fall block and tackle hook, which 75 latter engages the link m, upon which the die M, and its weight platform m', are suspended by means of flexible connections m², m².

The ends of the movable platform m', (to 80 the under side of which the convex die M, is rigidly secured) rest in vertical guide ways g, g, preferably consisting of angle plates attached to the inner sides of the corner uprights F², F², of the frame; and contact 85 rollers r, r, may be mounted on said ends of the weight platform m', to reduce frictional resistance and insure easy travel. The convex die M, when made of wood is provided with a metallic facing m³, for contacting directly with the surface of the wooden blank to be shaped. 90

The platform m', may be provided on its upper side with guard rails m'', m'', to insure the retention of the weights W, W, 95 placed on the platform to effect the bending of the prepared wooden blank, which latter consists ordinarily of a plank of uniform

width and thickness although other forms of blanks may be treated in similar manner. The weights are so arranged as to balance the platform and die evenly as related to the line of suspension, thus insuring pressure upon all parts of the blank during the operation of forcing it into the concave die.

As will be seen by reference more particularly to Figs. 3 and 4, the convex die M, 10 is recessed centrally and longitudinally,—this recess m^* , being for the accommodation of the take-up bolt t , of the blank holder and retainer T, the main portion of which consists of a strip of relatively thin elastic 15 resilient sheet metal t' , to the extremities of which are rigidly secured the clamp members t^2 , t^2 , formed with bifurcated end extensions t^3 , t^3 to straddle the aforesaid take-up bolt t .

20 s , s , are side guards on the dies which hold and support the blank B, laterally during the bending operation.

The manipulation of the blank B, is as follows: It is taken directly from the steam 25 chest where it has been saturated with moisture and inserted in a retainer T, of approximate length, with the clamp members t^2 , overlapping its ends, and a wedge t^4 is then inserted between one end and the 30 inner side of the adjacent clamp member to make a close fit and compensate for slight variations in the lengths of blanks. Thus incased on its lower side and ends it is positioned across the concave die N, with its 35 ends resting upon the die shelves n , n , and with one extremity against a gage shoulder n' , to centralize it in alinement with both dies M, N. The convex die M, is then lowered and forces the blank into the concave 40 die N, imparting to the blank the requisite shape or configuration. While the blank is still under the pressure of the convex die M, the take-up bolt rod t , is inserted through the longitudinal recess m^* , in said die and 45 dropped into the upturned bifurcated ends of the clamp members t^3 , of the retainer T, cylindrical washers t^5 , are applied to the ends of the bolt rod t , to bear against said ends of the clamp members t^3 , and hand 50 nuts t^6 , are applied to the threaded ends of the bolt rod and screwed up against the outer ends of said cylindrical washers t^4 , thereby binding the retainer T, as a whole to the bent blank in such manner that the 55 latter cannot yield when the pressure of the convex die is withdrawn. Hence when the convex die is raised sufficiently the bent blank and its retainer may be removed intact,—the shaped blank B, not being released from the retainer T, until the blank 60 has permanently set in form.

This operation may be repeated with successive blanks in an expeditious manner, the manipulation being simple and requiring

little or no skilled labor. As compared with 65 the old method of shaping blanks by screw pressure much economy is effected both in time, labor and cost of production, since the percentage of loss from blanks broken in treatment is reduced to the minimum owing 70 to the fact that the pressure is uniformly applied, and to the further fact that the blank while under treatment is reinforced and sustained by the retainer T. Furthermore the apparatus is very simple and inexpensive as compared with the complicated 75 apparatus heretofore used for the purpose, and the product is not only cheaper but superior in uniformity of shape and quality.

I have herein shown and described the 80 convex die M, as movable with relation to the concave die N, although it is obvious that this relationship might be reversed without departing from the spirit and intent of my invention, so that I do not limit 85 myself in this respect.

It will be seen that a distinctive feature of my invention consists in pivotally supporting the upper or movable die upon a flexible suspender in such manner as to allow said die to yield and adapt itself automatically to the work to be done, thereby obviating injury to the work; and in this connection the movable weights perform an important function in that while providing 90 adequate pressure they are not irresistible, and furthermore afford convenient means whereby the pressure may be lessened or augmented, or shifted and adjusted as may be found most expedient in adapting the 95 movable die to the requirements of the blanks operated upon.

What I claim as my invention and desire to secure by Letters Patent is,

1. In wood bending apparatus of the 105 character designated, in combination, a fixed lower concave die, and a movable upper convex die in alinement therewith, flexible means for pivotally suspending said movable convex die in such manner that it is 110 free to adapt itself to the work to be done, and hoisting mechanism connected with said flexible means of suspension, whereby said movable convex die may be raised or lowered with relation to the fixed concave die, 115 for the purpose described.

2. In wood bending apparatus of the character designated, in combination, a fixed lower concave die, and a movable upper convex die in alinement therewith, means for 120 supporting loose weights on said movable convex die, said loose weights, flexible means for pivotally suspending said movable and weighted convex die in such manner that it is free to adapt itself to the 125 work to be done, and hoisting mechanism connected with said flexible means of suspension, whereby said weighted movable

convex die may be raised or lowered with relation to the said fixed concave die, for the purpose described.

3. In wood bending apparatus of the character designated, in combination, a fixed lower concave die and a movable upper convex die in alinement therewith, means for supporting loose weights on said movable convex die, said loose weights, guide ways controlling the vertical movement of said weighted convex die, flexible means for pivotally suspending said weighted movable convex die in such manner that it is free to adapt itself to the work to be done, and hoisting mechanism connected with said flexible means of suspension, whereby said weighted movable convex die may be raised or lowered with relation to said fixed concave die, for the purpose described.
- 20 4. In wood bending apparatus of the character designated, in combination, a fixed lower concave die and a movable upper convex die in alinement therewith, means for supporting loose weights on said movable convex die, said loose weights, guide ways controlling the vertical movement of said weighted convex die, side guards extending beyond the opposed faces of said dies for the lateral support of the wooden blank therebetween, flexible means for pivotally suspending said weighted movable convex die in such manner that it is free to adapt itself to the work to be done, and hoisting mechanism connected with said flexible means of suspension, whereby said weighted movable convex die may be raised or lowered with relation to said fixed concave die, for the purpose described.

5. In wood bending apparatus of the character designated, in combination, a fixed lower concave die and a movable upper convex die in alinement therewith, said movable convex die being formed with a longitudinal recess in its face, means for supporting loose weights on said movable convex die, said movable weights, flexible means for pivotally suspending said weighted movable convex die in such manner that it is free to adapt itself to the work to be done, hoisting mechanism connected with said flexible means of suspension, whereby said weighted movable convex die may be raised and lowered with relation to said fixed concave die, and a blank retainer consisting of a strip of flexible metal formed with clamps adapted to embrace the ends of the wooden blank and with a take-up bolt engaging with the said clamps and adapted to extend through said longitudinal recess in the face of the weighted movable convex die, together with means for securing said clamps to said take-up rod, for the purpose described.
- 60 6. In wood bending apparatus of the character designated, in combination, a fixed

lower concave die and a movable upper convex die in alinement therewith, said movable convex die being formed with a longitudinal recess in its face, means for supporting loose weights on said movable convex die, said movable weights, flexible means for pivotally suspending said weighted movable convex die in such manner that it is free to adapt itself to the work to be done, hoisting mechanism connected with said flexible means of suspension, whereby said weighted movable convex die may be raised and lowered with relation to said fixed concave die, guide ways controlling the vertical movement of said weighted convex die, and a blank retainer consisting of a strip of flexible metal formed with clamps adapted to embrace the ends of the wooden blank and with a take-up bolt engaging with the said clamps and adapted to extend through said longitudinal recess in the face of the weighted movable convex die, together with means for securing said clamps to said take-up rod, for the purpose described.

7. In wood bending apparatus of the character designated, in combination, a fixed lower concave die and a movable upper convex die in alinement therewith, said movable convex die being formed with a longitudinal recess in its face, means for supporting loose weights on said movable convex die, said movable weights, flexible means for pivotally suspending said weighted movable convex die in such manner that it is free to adapt itself to the work to be done, hoisting mechanism connected with said flexible means of suspension, whereby said weighted movable convex die may be raised and lowered with relation to said fixed concave die, guide ways controlling the vertical movement of said weighted convex die, side guards extending beyond the opposed faces of said dies for the lateral support of the wooden blank therebetween, and a blank retainer consisting of a strip of flexible metal formed with clamps adapted to embrace the ends of the wooden blank and with a take-up bolt engaging with the said clamps and adapted to extend through said longitudinal recess in the face of the weighted movable convex die, together with means for securing said clamps to said take-up rod, for the purpose described.

8. In wood bending apparatus of the character designated, in combination, a concave die and a convex die, one stationary and the other movable, with relation thereto, the movable die being pivotally supported upon a flexible suspender, and hoisting mechanism connected with said flexible suspender whereby the movable die may be raised and lowered, for the purpose described.

9. In wood bending apparatus of the character designated, in combination, a con-

cave die and a convex die, one stationary and the other movable with relation thereto, the movable die being pivotally supported upon a flexible suspender and being provided with means for supporting loose weights thereon, said loose weights, and hoisting mechanism connected with said

flexible suspender whereby the said weighted movable die may be raised and lowered, for the purpose described.
